UNITED STATES PATENT OFFICE.

CHARLES F. OTT, OF BUCYRUS, OHIO.

INCUBATOR.

Application filed February 1, 1924. Serial No. 689,959.

To all whom it may concern:

Be it known that I, CHARLES F. OTT, a citizen of the United States, residing at Bucyrus, in the county of Crawford and 5 State of Ohio, have invented a new and useful Incubator, of which the following is a specification.

This invention aims to provide novel means for securing a proper circulation of 10 air in an incubator and for maintaining the air at a proper temperature.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood, that, within the scope of what is claimed, changes in the precise embodiment of the invention shown, can be made, without departing from 25 the spirit of the invention.

In the drawings:

Figure 1 shows in front elevation, a device constructed in accordance with the invention; Figure 2 is a plan of the tank; 30 Figure 3 is a sectional view illustrating the valve mechanism for the tank shown in Figure 2; Figure 4 is a transverse section of the incubator; Figure 5 is a top plan of the incubator; Figure 6 is a section of the incubator, the cutting plane in Figure 6 being at right angles to the cutting plane in Figure 4; Figure 7 is a plan of the floor of the casing.

The device forming the subject matter of 40 this application comprises a cabinet 1 including double walled ends 2, a back 3, a front 4, a top 44 and a bottom 5.

Within the cabinet 1 is disposed a casing 6 comprising a top 7, a bottom 8, a back 9, a front 10 and ends 11. The bottom 8 of the casing 6 is spaced but a small distance from the bottom 5 of the cabinet 1, the same observation holding true with respect to the back 9 of the casing 6 and the back 3 of the cabinet 1. Likewise, the front 10 of the casing 6 and the front 4 of the cabinet 1 are disposed relatively near to each other. Noting Figure 6, it will be observed that the ends 11 of the casing 6 are spaced at considerable distance from the ends 2 of the cabi-

net 1, the top 44 of the cabinet 1 being spaced at some distance from the top 7 of the casing 6. The ends 11 of the casing 6 are spaced from the bottom 8 of the casing, so that openings 12 exist in the ends of 60 the casing 6, at the bottom of the casing, as a comparison of Figures 6 and 4 will show. The front 10 of the casing 6 has a doorway 14, registering with a doorway 15 in the front 4 of the cabinet 1, the doorways being controlled by a door 16 hinged to the front 4 of the cabinet 1. A frame 17 is located between the parts 10 and 4 and extends about the doorways 14 and 15, to prevent the escape of air through the doorways, from the space which exists between the casing 6 and the cabinet 1—an observation which will be understood better after the circulation of air has been traced out. Access to the lower portion of the casing 6 70 is had by way of an auxiliary door 18, located below the door 16 and hinged to the front 4 of the cabinet 1. The door 18 gives access to a tank 28 hereinafter described. A supplemental door 19 is hinged to the 75 front 4 of the cabinet 1 and is located at one end of the door 16. The door 19 gives access to certain of the driving mechanisms hereinafter described and shown at the left hand end of Figure 6.

Partitions 20 of inverted U-shape extend between the top 7 of the casing 6 and the top 44 of the cabinet 1, the partitions extending downwardly between the ends 11 of the casing 6 and the ends 2 of the cabinet 1, 80 as shown in Figure 6, the partitions cooperating to define an inverted U-shaped passage, clearly indicated in Figure 6 and marked by the reference numeral 21 in Figure 4. In the ends 11 of the casing 95 6, near to the top of the casing, there are openings 22, located on opposite sides of the depending ends of the passage 21. The top 44 of the cabinet 1 is supplied with fresh air openings 23, communicating with the passage 21, as shown in Figure 6. The top 44 of the cabinet 1 has foul air outlet holes 24. These holes 24 do not communicate with the passage 21 but do communicate with the space between the top 44 of the cabinet 1 and the top 7 of the casing 6 100 externally of the passage 21.

A floor 25 extends across the casing 6, near to the lower end thereof, and is provided with a plurality of apertures 26, a 110

layer of netting 27 or the like, being mounted on the floor 25. A T-shaped water tank 28 rests on the bottom 8 of the casing 6 and includes a head 29 and an arm 30, the arm 5 extending outwardly through the front 10—4 as shown best in Figure 4. There are openings 31 in the top of the head 29 of the water tank 28. Figure 3 shows that there is an opening 32 in the outer end of the 10 arm 30 of the tank 28, the opening 32 being located at the top of the arm so that a quantity of water may be held in the tank 28. A valve 33 in the form of a cap, is mounted to rotate on the outer end of the 15 arm 30 of the tank 28, and has an opening 34, adapted to register with the opening 32 in the arm 30 of the tank 28. By rotating the valve 30, the openings 34 and 32 may be brought more or less into registration, 20 thereby governing the amount of air which enters the tank, and by rotating the cap or valve 33 through an arc of 180 degrees from the position shown in Figure 3, the opening 32 may be closed entirely, and the supply of 25 air cut off completely.

A flue 35 is mounted in the top 44 of the cabinet 1 and in the top 7 of the casing 6, and communicates with the compartment 36 which exists in the casing 6 above the floor 25. As shown in Figure 4, the flue 35 passes across the passage 21, but there is no communication between the flue and the passage. The flue 35 is controlled by a damper 37 under the governance of a thermostat 38.

The air within the incubator may be heated in any desired way, but, if preferred, a water coil 39 may be located below the floor 25, the coil communicating with a heating tank 40, a pipe 42 connecting the heating 40 tank 40 with an expansion tank 41, shown in Figure 1. The heater for the tank 40 is marked by the numeral 43 and is regulated by a damper 46 controlled by a thermostat 45.

Before alluding to the means whereby the eggs are mounted in the incubator, the circulation of air will be traced out.

When the thermostat damper 37 is closed, air rises through the eggs, and goes out of the egg compartment through the openings 22. There it divides, part going up and out through the holes 24, and part going down through the openings 12, and up again through the eggs. The air that goes out through the holes 24 is replaced, partly, by unmoistened air, through the openings 23 and the passage 21, and partly by moistened air through the part 30. By adjusting the valve 33, the attendant can govern the ratio 55 of fresh moistened air to that of fresh unmoistened air, that is supplied to the eggs, and so govern the humidity of air around the eggs.

Passing to the means whereby the eggs 60 are carried, it will be observed referring

particularly to Figure 6, that a main shaft 47 is journaled in the end walls 11 and 2 of the incubator, an auxiliary shaft 48 being supported likewise. The shafts 48 and 47 are connected operatively by intermeshing gear 70 wheels 49. The shaft 48 carries a worm wheel 50 cooperating with a worm 51 on a shaft 52, the shaft 52 being disposed at right angles to the shafts 48 and 47, and being driven by a motor 53 (Figure 1) 75 mounted on the front 4 of the cabinet 1. Disk-like heads 54 are secured to the shaft 47 and are located within the casing 6, the heads being connected by supports 55, in the form of rods. Egg carriers 56 are mounted 80 at 58, for swinging movement, on the supports or rods 55, each egg carrier being provided with a hinged door 7, adapted to be opened, as shown in Figure 4, when the door 16 is opened, to permit the eggs to be placed 85 in the carriers 56. The eggs may be mounted in trays 59 of any desired construction, supported within the carriers. Any suitable means may be provided for turning the eggs, but, since a specific form of egg turner 90 cannot be covered in this application, no egg turner is shown or described.

The motor 53 drives the shaft 52, the shaft 52 imparting rotation to the shaft 48 by way of the worm 51 and the worm wheel 50. The gear wheels 49 transmit motion to the shaft 47, and when the shaft 47 is rotated, the egg carriers 56 will move in an orbit between the top portion of the compartment 36 and the bottom portion thereof. The air in the top portion of the compartment 6 is warmer than the air in the lower portion of the compartment, or, at least there is not a uniform temperature in the air at all 105 points between the top and the bottom of the compartment. Since the egg carriers 56 move slowly in an orbit, the eggs in the various carriers all will have the same treatment and will be subjected to an average 110 temperature.

The circulation of the air has been described hereinbefore, and the description need not be alluded to at this point.

The device forming the subject matter of this application provides for a continuous circulation of air in the incubator. As the air is heated, it rises and passes through the eggs and, then, moves downwardly, the cycle being repeated, an even temperature being obtained. It is to be observed that 115 this device is compact in construction.

Having thus described the invention, what I claim as new is:

1. An incubator comprising a cabinet, a casing within the cabinet, and provided at its ends with upper and lower openings and an inverted U-shaped flue extended across the top of the casing and downwardly along the ends of the casing, the upper openings 120 communicating with the space between the 125

cabinet and the casing, independently of the flue, the top of the cabinet having an inlet opening communicating with the flue, and having an air outlet opening independent of the flue and communicating with the space between the top of the casing and the top of the cabinet, an air outlet flue communicating with the interior of the casing, means for controlling the passage of air through the last specified flue thermosytatically, means for heating the air within the casing, a rotary member journaled in the casing, egg carrying means on the rotary member, and means for operating the rotary member.

2. In a device of the class described, a cabinet having a doorway, means for heating the cabinet, a rotary member journaled in the cabinet for movement about an approximately horizontal axis, means for rotating said member, an egg carrier mounted to swing on the rotary member, and a closure hinged to the carrier and adapted to be swung to an open position through the doorway, to serve as a platform. 20

In testimony that I claim the foregoing as my own, I have hereto affixed my signature. 25

CHARLES F. OTT.
